UNITED STATES PATENT OFFICE.

HERBERT J. STRAKER, OF ATTLEBOROUGH, MASSACHUSETTS, ASSIGNOR
TO GEORGE K. WEBSTER, OF SAME PLACE.

CHAIN.

SPECIFICATION forming part of Letters Patent No. 656,677, dated August 28, 1900.

Application filed January 3, 1900. Serial No. 232. (No model.)

To all whom it may concern:

Be it known that I, HERBERT J. STRAKER, a citizen of the United States, residing at North Attleborough, in the county of Bristol 5 and State of Massachusetts, have invented certain new and useful Improvements in Chains, of which the following is a specification, reference being had therein to the accompanying drawings.

10 My invention relates particularly to that class of chains which are used in the construction of bracelets; and it consists in the novel construction of their parts.

15 My purpose is to so construct the chain-links as to produce a light-weight chain or one free from the indentations which now characterize this class of chains.

It is now customary to engage the links of 20 bracelet-chains before curbing or twisting the same, as has always been done in the manufacture of other kinds of chains. The twisting operation always results in an indentation of the links at their points of engagement. Again, very thin stock is not now utilized 25 for this purpose, because of its incapacity to sustain the torsional strain.

I attain the objects of my invention by the construction hereinafter described.

Figure 1 is a side view of my completed 30 links in engagement; Fig. 2, a perspective view of a struck blank; Figs. 3 and 4, like views of the respective link-sections. Fig. 5 is a sectional view of a completed link on line $z-z$ of Fig. 1, and Fig. 6 shows the plan of 35 a cast of the die by which the blank in Fig. 2 is shaped.

In the above figures, A is a blank of thin stock struck by a die whose outline is shown as B in Fig. 5, which has an irregularly- 40 swelled or billowy surface, with an oblong ring o in relief thereon, said ring being bounded on its exterior and interior by slight elevations or shoulders s and s' . It will be noted that the resulting impression upon the blank 45 A is an oblong ring a , with exterior and interior

shoulders b and b' , all in relief upon a blank, of which they are a part, whose surface partakes of the irregular swell imparted by the die. The section a , with its bounding shoulders or flanges b and b' , is next cut 50 from the blank A in the usual manner. By a similar process, using a die which has no shoulder, I produce a link-section a' which differs from section a only in the omission of the shoulders or flanges b and b' . 55

I assemble and solder the link-sections a and a' by joining the edges of the section a' to the corresponding flanged edges of a in such a position that the latter slightly overlaps the former and forms a soldering-face. 60 These completed links may be engaged in the usual manner, which consists in transversely sawing each alternate link and soldering the joints after being sprung into engagement. The resulting chain, as shown in 65 Fig. 1, presents a twisted or curbed appearance without the necessity of further manipulation.

Having thus described my invention, what I claim as new, and desire to secure by Letters 70 Patent, is—

1. A chain having links composed of two concavo-convex longitudinal link-sections, each section struck up with a half-twist having their respective adjacent edges united by 75 solder, as and for the purpose set forth.

2. A chain having links composed of two concavo-convex longitudinal link-sections, each section struck up with a half-twist and one of said sections having its edges bounded 80 by a continuous flange and both sections joined by solder as and for the purpose set forth.

In testimony whereof I affix my signature in presence of two witnesses.

HERBERT J. STRAKER.

Witnesses:

WILLIAM F. MARSHALL,
HORATIO E. BELLOWES.
